UNITED STATES PATENT OFFICE.

CHARLES ANSPACH, OF BROWNLEE, NEBRASKA.

FOLDING EGG CRATE.

Application filed June 12, 1922. Serial No. 567,668.

To all whom it may concern:

Be it known that I, CHARLES ANSPACH, a citizen of the United States, residing at Brownlee, in the county of Cherry and 5 State of Nebraska, have invented certain new and useful Improvements in Folding Egg Crates, of which the following is a specification, reference being had to the accompanying drawings.

10 This invention relates to folding crates, and has for its object to provide a crate capable of being folded into a compact form without interfering with the substantial qualities of the bottom and sides.

15 It is another object of the invention to provide a crate of this character wherein the sides are movably connected to the bottom by means carried by the bottom, said means permitting movement of the sides 20 vertically with respect to the bottom and also laterally with respect to the bottom.

It is a further object of the invention to provide a crate of this character including sides which are connected to the bottom for 25 substantially universal movement, the crate being provided with ends adapted to extend between and substantially brace the sides in their extended positions.

It is a still further object of the invention 30 to provide a crate of this character including movably connected sides and ends, the sides being connected to the bottom of the crate by means of a brace projecting from the bottom, said brace having slots for the 35 reception of a pin carried by portions of the sides, said slots having recesses adapted to receive the pins to prevent movement of the sides under certain conditions.

With these and other objects in view, the 40 invention consists in the improved construction and arrangement of parts to be herein-after more particularly described, fully claimed and illustrated in the accompanying drawings, in which:

45 Figure 1 is a longitudinal sectional view of a folding crate constructed in accordance with an embodiment of the invention;

Figure 2 is an end elevation of the structure in its extended position;

50 Figure 3 is an end elevation of the structure in its folded position;

Figure 4 is a section taken on the line 4-4 of Figure 1;

55 Figure 5 is a fragmentary plan view of one corner of the plate showing the socket for the reception of the fastener 29; and

Figure 6 is a fragmentary end elevation showing the hook for fastening the cover to the plate.

Referring to the drawings, 5 designates a 60 bottom including end beams 6 and 7 and a center beam 8, said beams extending laterally of the bottom, and to which the boards, or material forming the bottom, are connected. Each of the beams 6, 7 and 8 has its 65 end portions slotted for the reception of a supporting member 9, each supporting member consisting of a right angular piece of metal including arms 10 and 11, the arm 10 being adapted to extend into the slots of 70 the beams, while the arm 11 is intended to project above the beams substantially at right angles thereto and adjacent the extremities of the beams. The arm 11 is provided with an elongated slot 12, one portion 75 of each end portion of said slot being enlarged as at 13 to substantially provide bayonet slots through the cooperation of the slot 12.

In connection with the bottom, side members or walls 14 and 15 are provided, each of said walls comprising end beams 16 and 17 and an intermediate beam 18, the lower ends of each beam being provided with slots 19 adapted to receive the adjacent arm 11 80 of the supporting members of the bottom.

A pivot pin 20 is passed through the lower ends of the beams 16, 17 and 18 and through the slot 12 for pivotally connecting the side walls to the bottom. By this 90 means the side walls may be moved vertically with respect to the bottom in the opening and closing of the crate. When the pin 20 is disposed in the bayonet slot portion at the junction of the arm 11 with the arm 10, 95 movement of the sides in any direction is prevented. However, when it is desired to fold the crate, the side is moved inwardly so as to disengage the pin from the bayonet portion of the slot so as to permit movement of the pin upwardly in the slot 12 and likewise movement of the side member or wall.

Secured to the outer face of each of the beams 6 and 7 is a pair of hinged sections 21 adapted to receive a pintle 22. Disposed between the side members 14 and 15 of the crate are end members 23 and 24, each end member being provided with a pair of hinged sections 25 adapted to receive the 105 pintle 22, for pivotally connecting the end members to the bottom. Each of the end members is provided at its upper end with a 110

brace and locking member 26, the end portions of the inner face of said member being reduced, said reduced portions cooperating with the end wall to provide sockets 27, a 5 pin 27^a being disposed in each socket. Projecting from the central portion of the outer face of the bracing member of the end 23 is a keeper 28, the purpose of which will be hereinafter described.

- 10 In order to connect the end members in their extended position to the side members, each of the beams 16 and 17 has pivoted to its outer face a fastener 29, said fastener including a finger piece and stop 29^a and 15 a finger 30, the finger 30 being adapted to extend into the socket 27 and engage the pin 27^a. By this means the end members or walls are held between the side members or walls to prevent movement of the pins 20 20 of the side members into the slot 12 and consequently prevent accidental folding or collapsing of the crate.

In connection with the crate, a detachable cover is provided, said cover having 25 depending flanges at its end portions, the end portion of said cover adjacent the end 23 of the crate being provided with a catch 31, said catch extending over the flange of the cover and having a lip 32 adapted to 30 extend into and engage the keeper 28 of the end 23. The opposite end of the cover is provided with a hook 28^a or like fastening means for securing the cover to the crate in connection with the catch 31.

- 35 Assuming that the crate is in its extended position and it is desired to fold the same, the hook of the cover is released from the end 24 and the cover raised, so as to disengage the lip from the keeper 28. The 40 fasteners 29 are then swung upwardly through the medium of the finger piece 29^a, so as to release the ends 23 and 24 from the sides 14 and 15. The ends are then permitted to swing outwardly as far as possible 45 so as to permit the sides to move inwardly out of the bayonet portions of the slots 12 to permit the pins 20 to enter the major portion of the slots 12. The side walls may then be moved upwardly to the upper 50 bayonet portions of the slots 12, so as to permit free oscillating movement in the last mentioned bayonet portion of the slot. The end members are then swung inwardly into engagement with the bottom, the cover applied upon the ends and then the rear and 55 front sides swung inwardly from the top of the supporting members, the length of the arm 11 of the supporting members per-

mitting the ends and cover to be compactly disposed beneath the sides.

From the foregoing it will be readily seen that this invention provides a novel form of crate having novel means of connecting the sides to the ends, said means not only bracing the sides with respect to the bottom, but 65 serving as pivot means to permit the crate to be readily collapsed and extended. Another important feature is that in addition to the ends being foldable, they also serve to brace the sides when the latter are in 70 their extended positions.

What is claimed is:—

1. A folding crate comprising a bottom including transversely extending end beam members, supporting members projecting upwardly from the ends of each of the beams, each of said supporting members having a longitudinally extending slot, a portion of each of the end portions of said slots being enlarged to provide a bayonet 80 slot, side members having beams extending transversely of the end portions of said side members, each of said beams being slotted for the reception of the supporting members, and pins extending through the slotted ends of the beams, of the side members, 85 said pins being arranged to engage the bayonet portions of the slots of the supporting arm, to prevent movement of said side members longitudinally of the slot, end members hinged to the beams of the bottom and arranged for movement between the side members, and means for connecting the end members to the side members.

2. A folding crate comprising a bottom, 95 supporting members projecting upwardly from the ends thereof, each of said supporting members having a longitudinally extending slot, a portion of each of the end portions of said slots being enlarged to provide a bayonet slot, side members extending transversely of the supporting members, 100 said side members being slotted for reception of the supporting members, and pins extending through the slotted portions of the side members and arranged to engage the bayonet portions of the slots of the supporting arms to prevent movement of said side members longitudinally of the slots, end members hinged to the bottom and arranged for movement between the side members, and means for connecting the end members to the side members.

In testimony whereof I hereunto affix my signature.

CHARLES ANSPACH.
